CLAIM

The ornamental design for a protective cover skin for electronic device, as shown and described.

DESCRIPTION

FIG. 1 is a front, top and right perspective view of protective cover skin for electronic device showing claimed design; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom and right perspective view thereof; and,

FIG. 9 is a front, top and right perspective view thereof, with a top portion open in use.

The broken lines shown in FIG. 3 depict a portion of the protective cover for electronic device but form no part of the claimed design. The broken lines shown in FIG. 9 depict environment and form no part of the claimed design.

1 Claim, 8 Drawing Sheets
